UNITED STATES PATENT OFFICE.

JAMES C. CHESTER, OF ESCALON, CALIFORNIA.

SIGNAL.

1,256,773.

Specification of Letters Patent. Patented Feb. 19, 1918.

Application filed June 12, 1917. Serial No. 174,212.

To all whom it may concern:

Be it known that I, JAMES C. CHESTER, a citizen of the United States, residing at Escalon, in the county of San Joaquin, State 5 of California, have invented certain new and useful Improvements in Signals; and I do declare the following to be a full, clear, and exact description of the same, reference being had to the accompanying drawings, 10 and to the characters of reference marked thereon, which form a part of this application.

This invention relates to improvements in signals and particularly to a signal adapted 15 to be mounted upon a vehicle whereby the driver of such vehicle may give an indication to other vehicles or pedestrians to the front or rear of him that he is about to turn. The invention will be preferably 20 mounted at or near the driving seat of the vehicle and is easily operable by hand to extend the same. When not in extended position it is held within the casing by resilient means of desired type. A light is provided 25 at the end of the signal whereby it can be readily seen in the dark.

A great many accidents occur due to the fact that vehicles turn or stop suddenly without giving any previous indication that 30 they are about to do so. Laws have been enacted requiring the driver of a vehicle to extend his hand but this is often inconvenient and in inclosed cars is impossible. My improved signal however, will be much 35 more efficient than the extending of the hand and at the same time will not require the driver to let go of his steering wheel at a time it is very essential that he have full control of his vehicle and at the same time 40 can be quickly and easily extended at any moment to show the direction the driver intends to turn at his first opportunity.

A further object of the invention is to produce a simple and inexpensive device and 45 yet one which will be exceedingly effective for the purposes for which it is designed, to give a warning to all in plenty of time as to the intention of the driver.

These objects I accomplish by means of 50 such structure and relative arrangement of parts as will fully appear by a perusal of the following specification and claims.

In the drawings similar characters of reference indicate corresponding parts in the 55 several views.

Figure 1 is a front elevation of a motor vehicle showing my improved mechanism mounted thereon.

Fig. 2 is a sectional view through the casing of the signal showing the signal in 60 extended position.

Fig. 3 is a vertical sectional view of the signal extending mechanism.

Referring now more particularly to the characters of reference on the drawings the 65 numeral 1 designates the casing for the signal which may be of any desired construction and mounted at a point on the vehicle at or near the driving seat thereof. Disposed vertically within the casing 1 in any 70 suitable manner is a pin 2 having for a portion of its length a spiral bar 3. The numeral 4 designates a small roller having a central slot 5, on each side of which is a small roller 6 whereby the roller 4 may 75 move easily in a rotary manner up and down the spiral bar 3. This roller 4 is held in its uppermost position on the spiral bar 3 by means of a coil spring 7 interposed between the top of the casing 1 and the roller 80 4 so as to pull such roller upwardly. Rolled up on the roller 4 is a signal flag 8, the rolled up position of such flag 8 being occasioned by the rotary motion of the said roller 4 in the manner described. When not in use the 85

flag 8 is rolled on the said roller 4 within the casing 1. When it is desired to extend the flag, however, this is accomplished by means of the following structure and operation, namely: A hand button 9 is provided 90 with a pin 10 turnably disposed through the casing 1. On this pin 10 within such casing 1 is secured a rod 11 pivotally connected at its opposite end with the flag 8 as at 12. When it is desired to extend the signal the 95

member 9 is turned which turns the pin 10 and moves the rod 11 out of the casing 1 in an arc. Since the rod 11 is pivotally connected to the flag 8 this unrolls such flag 8 and extends it substantially in the manner 100 shown in Figs. 1 and 2. As the flag 8 is unrolled it of course must likewise describe an arc to conform to the arc as described by the rod 11. This is permitted of by the roller 4 moving downwardly on the spiral bar 3. When once extended the signal may 105 be held in that position by means of a small lug 13 on a collar 14 fixed to the pin 10 which lug engages a corresponding groove in the casing. The pin 10 is movable lon- 110

gitudinally through the casing 1 against the pressure of a spring 15 whereby the lug 13 may be engaged or disengaged with the corresponding groove. In the outer end of the 5 rod 11 is an electric lamp 16 which is provided with suitable wire connections whereby at night the lamp will be lighted when the signal is extended. These electrical connections will be of a general type hence 10 I do not here specifically describe the same. When the signal has served its purpose the operator grasps the member 9 and presses the pin 10 against the pressure of the spring 15. This releases the lug 13 from its groove 15 and the spring 7 then pulls all the parts back into folded position within the casing 1 where they remain until again extended in the manner described.

From the foregoing description it will be 20 readily seen that I have produced such a device as substantially fulfills the object of the invention as set forth herein.

While this specification sets forth in detail the present and preferred construction 25 of the device, still in practice such deviations from such detail may be resorted to as do not form a departure from the spirit of the invention, as defined by the appended claims.

30 Having thus described my invention what

I claim as new and useful and desire to secure by Letters Patent is:

1. A signal comprising a casing, a spiral bar mounted in the casing, a roller mounted for vertical and rotary motion on the bar, a flag wound on the roller, and means for moving the roller over the bar to unwind the flag thereon. 35

2. A signal comprising a casing, a spiral bar mounted in the casing, a roller mounted for vertical and rotary motion on the bar, a flag wound on the roller, and means for moving the roller over the bar to unwind the flag thereon, such means including a pivoted rod connected with the free end of the flag 45 and means for moving the rod on its pivotal point.

3. A signal comprising a casing, a spiral bar mounted in the casing, a roller mounted for vertical and rotary motion on the bar, a flag wound on the roller, and means for moving the roller over the bar to unwind the flag thereon, such means including a pivoted rod connected with the free end of the flag 50 and means for moving the rod on its pivotal point, and fixing it in a position to hold the flag extended. 55

In testimony whereof I affix my signature.

JAMES C. CHESTER.
